UNITED STATES PATENT OFFICE.

HARRY SEBELL, OF BOSTON, MASSACHUSETTS, ASSIGNOR TO ARTHUR H. PARKER, OF LEXINGTON, MASSACHUSETTS.

CAN.

Application filed January 5, 1925. Serial No. 514.

This invention relates to an hermetic seal for a can and particularly to that type of hermetic seal in which the can body is provided at its top with an outwardly-extending sealing flange and the cover which sets into the open top of the can is also provided with an outwardly-extending sealing flange adapted to overlie the sealing flange of the can body, said sealing flanges being held in sealing relation by a U-shaped sealing strip which embraces them.

One of the objects of my present invention is to provide an improved construction of sealing strip and an improved manner of locking the sealing strip in place by virtue of which the sealing strip may be more readily removed when it is desired to open the can and during its removal it will loosen the cover thus facilitating the opening of the can.

Other objects of the invention are to improve generally hermetically-sealed cans all as hereinafter set forth.

In order to give an understanding of the invention I have illustrated in the drawings a selected embodiment thereof which will now be described after which the novel features will be pointed out in the appended claims.

Fig. 1 is a perspective view of a can made in accordance with my invention;

Fig. 2 is a sectional view through the upper end of the can and the can top showing them separated from each other;

Fig. 3 is a sectional view showing the can after it has been sealed;

Fig. 4 is a fragmentary perspective view of the sealing strip.

Fig. 5 is a section on the line 5—5, Fig. 4;

Figs. 6, 7 and 8 are fragmentary views showing steps in the process of forming the can cover.

1 indicates the can body which is provided with the open top 2 and is also formed with the outwardly-extending lateral sealing flange 3 at the top. The can top or can cover is indicated generally at 4 and it is of the type which is adapted to fit tightly into the open top 2 of the can 1. This can top is also provided with the outwardly-extending lateral sealing flange 5 which is adapted to overlie the sealing flange 3 of the can body when the cover is in place, a gasket 6 preferably being employed between

the sealing flanges to assist in making a 55 tight joint.

The two sealing flanges 3 and 5 are held in their sealing relation by means of a U-shaped sealing strip 7 which embraces the flanges and clamps them tightly against the 60 gasket 6.

To hold the sealing strip in place I have formed the cover 4 with a locking flange 8 which extends outwardly from the inner edge of the sealing flange 5 and is adapted 65 to overlie the upper leg 9 of the sealing strip. The outer peripheral edge 10 of the locking flange 8 is bent downwardly to partially embrace the sealing strip thereby to hold it firmly in place. When the cover top 70 is first made the locking flange 8 will have a flat shape as shown in Fig. 2 and will be spaced from the sealing flange 5 so as to form a groove 11 into which the upper leg 9 of the sealing strip may be inserted during 75 the can-sealing operation.

The locking flange is of sufficient width so that it projects slightly beyond the sealing strip as shown in dotted lines Fig. 3 and after the sealing strip is in place the edge 80 10 of the locking flange is spun downwardly to engage the outer rounded face of the sealing strip and thus lock said strip firmly in place.

A convenient way of making the cover 4 85 with both the sealing flange 5 and the locking flange 8 is illustrated in Figs. 2, 6, 7 and 8. The first step in the operation of making the can top will be to form it with the up-standing peripheral flange 15 as 90 shown in Fig. 6. This flange is then acted on by suitable dies so that a portion thereof intermediate its edge is bent outwardly as shown in Fig. 7 and the two sides 12 and 13 of the outwardly bent portion are then 95 pressed together to form the sealing flange 5. Subsequently the upper portion of the can top is bent outwardly to form the flange 8 as illustrated in dotted lines Fig. 8 and in Fig. 2. This flange 8 is so shaped that it is 100 separated from the sealing flange 5 by the groove 11. The sealing flange 5 of the cover is thus made of double thickness and the locking flange 8 is connected to the sealing flange at the inner edge thereof.

It will be understood, of course, that after the sealing strip has been inserted pressure is applied to the assembled sealing flanges,

sealing strip and locking flange in a direction transverse thereto to press them firmly together and during this operation the peripheral edge 10 of the locking strip may be bent into its locking engagement with the sealing strip.

To facilitate opening of the can I propose to form the sealing strip with an extension 14 which will preferably be circular in cross section. After the sealing strip has been inserted in place the extension 14 thereon may be bent to lie against the can body either by bending it downwardly as shown in Figs. 1 and 3 or by bending it laterally to lie under the sealing flange.

When the can is to be opened the extension 14 will be grasped and pulled outwardly and in this way the end of the sealing strip to which the extension is secured will be withdrawn from its sealing engagement with the sealing flanges. During such withdrawal the peripheral edge 10 of the locking strip will be bent upwardly sufficiently to allow the sealing strip to be withdrawn. The withdrawal of the sealing strip proceeds progressively around the can and during this withdrawing operation the sealing strip will apply upward pressure on the locking flange which will tend to loosen the can cover so that when substantially the entire length of the sealing strip has been withdrawn the cover will be found to be loose in the can top and may be easily removed.

The advantage of having the extension 14 cylindrical or round in shape is that it can be freely handled in opening the can with-

out danger of injury to the person using it. I claim.

1. In a can, the combination with a can body having a laterally-extending sealing flange, of a can cover having a vertical wall portion adapted to fit within the open top of the can body, said wall portion having formed therein an outwardly-extending fold which constitutes a two-ply sealing flange to cooperate with the sealing flange of the can body, a U-shaped sealing strip embracing said sealing flanges, the upper edge of the wall portion of the cover being bent outwardly to form a one-ply locking flange which overlies the upper leg of the sealing strip.

2. In a can, the combination with a can body having a laterally-extending sealing flange, of a can cover having a vertical wall portion adapted to fit within the open top of the can body, said wall portion having formed therein an outwardly-extending fold which constitutes a two-ply sealing flange to cooperate with the sealing flange of the can body, a U-shaped sealing strip embracing said sealing flanges, the upper edge of the wall portion of the cover being bent outwardly to form a one-ply locking flange which overlies the upper leg of the sealing strip, and the peripheral edge of said locking flange being bent to partially embrace the sealing strip thereby to lock the latter in place.

In testimony whereof, I have signed my name to this specification.

HARRY SEBELL.
